UNITED STATES PATENT OFFICE.

FAY T. RODGERS, OF MEMPHIS, TENNESSEE.

REFRIGERATOR.

Application filed July 24, 1926. Serial No. 124,648.

This invention has general reference to refrigerators that have ice containers placed in either or both ends thereof, but relates more particularly to a special construction and arrangement of the drip pan or pans disposed beneath such containers. Also, it has reference to the drain pipe leading from a plurality of ice containers arranged one above another, such as are shown in the 10 United States Letters Patent heretofore issued to me, No. 1,567,082, dated December 29, 1925.

In refrigerators, it is extremely important that advantage be taken of as much as possible of the cooling action of the cooling medium employed, which usually is ice, and that, in furtherance of this purpose, as much as possible of the cooling value of the water formed from the melted ice be conserved 20 and taken advantage of. Heretofore, in an effort to accomplish this desirable object, use has been made of a complicated system of pipes and pans, whereas, by the present invention, the desired result is secured by 25 simple and inexpensive means, and with a maximum of efficiency.

The principal objects of this invention are—

First, to provide means whereby a large 30 surface area of the drip water is exposed to the air in the refrigerator;

Second, to provide means for retarding the run-off or waste flow of the drip water, in order to take the greatest possible advantage of the cooling value thereof;

Third, to obviate storage of the drip water in what may be termed the food section of the refrigerator; and

Fourth, to simplify and improve the construction and arrangement of the drip pan or pans.

The means by which I accomplish the foregoing and other objects of my invention, and the manner of their accomplishment, 45 readily will be understood from the following description on reference to the accompanying drawings, in which—

Fig. 1 is a perspective view, in sectional elevation, of a refrigerator embodying my 50 improvements, the front part of the case being cut away substantially along the line 1—1 of Fig. 2, and a plurality of containers and their supports being shown in place in one end of the case, while only the drip pan 55 is shown in the other end.

Fig. 2 is a sectional plan of the inner lining of the refrigerator, taken substantially on line II—II of Fig. 3, showing the drip pans and the drains therefrom.

Fig. 3 is a fragmentary sectional elevation, taken substantially on the line III—III of Fig. 2.

Referring now to the drawings in detail, 10 is the exterior case of the refrigerator; 11 is a water-tight lining, of metal or other suitable material, forming the interior of the case; the numerals 12 refer to refrigerant containers, one or more of which may be used at either end of the case; the parts indicated by 13 are drip valves, each of 15 which discharges into a joint drip pipe 14, said pipe preferably being removably supported by a hook 15, from which it may be disconnected to permit unitary removal of the refrigerant containers. One such drip 20 pipe is used for each bank of containers, and said pipe or pipes discharge into a drip pan below the containers, said pan being formed by partitioning off a portion of the bottom of the inner lining of the case, by 25 means of a cross member or plate 16, which extends from the front of the lining to its back, and is connected by a water-tight joint, as by soldering, with the bottom, front and back of said lining. A depression 17 is 30 formed in the cross member 16, and from said depression a channel-way 18 constitutes a drain to a drip pipe 19, which may be provided with a cup-shaped cover 20, having notches 21 in the lower edge thereof, to 35 permit water to pass to the drip pipe.

The piece from which the channel-way 40 18 is formed, preferably constitutes only one side and the bottom thereof, said bottom being joined to the back wall of the lining of the case, as by solder, and one end of the channel side and bottom being similarly connected with the cross member 16, at the point where the depression 17 occurs. A wedge-shaped member 22, placed beneath 45 the channel-way 18, gives the latter the proper inclination for drainage.

Should it be desired to increase the length 50 of flow of the water in the drip pans, a division plate or partition 23 may be disposed diagonally across one or more of the pans, being secured in place in the same manner as the member 16.

It will of course be understood that the 55 drawings herein are for purposes of illustra- 60

tion only, and that I do not wish to be limited to the construction shown, except as it may be specified hereinafter in the claims.

Having thus described the invention, 5 what is claimed is:

1. In a refrigerator, a plurality of individual refrigerant containers, a common drip pipe therefrom, means connecting each of said containers with said drip pipe, said pipe being removable independently of said containers and said containers being individually removable from the refrigerator, and a drip pan into which said pipe discharges.
- 10 2. In a refrigerator, a plurality of refrigerant containers, an independently-removable drip pipe into which each of said con-

tainers discharges, and a non-removable drip pan, permanently secured to the refrigerator, into which the drip from said pipe is delivered.

3. In a refrigerator, a plurality of refrigerant containers, and an independently removable drip pipe into which each of said containers discharges.

4. In a refrigerator, a plurality of refrigerant containers, each independently removable from said refrigerator, and an independently removable drip pipe into which each of said containers discharges.

In testimony of the foregoing, I affix my signature.

FAY T. RODGERS.
